UNITED STATES PATENT OFFICE.

JOSE MARINO AGONCILLO, OF SAMPOLOC, PHILIPPINE ISLANDS.

COMBINED CASE AND CIGARETTE MACHINE.

Application filed May 4, 1925. Serial No. 27,907.

My present invention has reference to a combined tobacco box and a cigarette maker.

My object is to combine in a unitary structure a combined tobacco box or receptacle and a cigarette maker of such nature and construction as to render the same cheaply manufactured and thoroughly effective for the purposes designed.

For a full and comprehensive understanding of the invention, reference is to be had to the accompanying drawings, in which there is illustrated a simple and satisfactory embodiment of the improvement reduced to practice.

15 In the drawings:—

Figure 1 is a side elevation of the improvement, showing the parts of the cigarette maker removed from the can or container, as when a cigarette is to be formed.

20 Figure 2 is a side elevation of the improvement.

Figure 3 is an approximately central longitudinal sectional view through the improvement, as disclosed in Figure 2.

25 Figure 4 is a sectional view on the line 4—4 of Figure 3.

Figure 5 is a sectional view on the line 5—5 of Figure 3.

30 Figure 6 is a view looking toward the top of the container.

Figure 7 is a view of the tobacco directing tube that has the cigarette paper wound therearound and also a sectional view of the tube in which the first mentioned tube is received.

35 Figure 8 is a sectional view on the line 8—8 of Figure 3.

The tobacco container 1 is preferably of the usual construction, the same being provided with an open top closed by a hinged and flanged cover 2. The cover is latched in closed condition on the container in the usual manner, as for instance, by means 3 (Figures 1 and 2).

40 The edges of the container are rounded, and secured in the container, adjacent to one of the said edges there is a partition 4. The partition extends from the closed bottom 5 of the container and terminates a suitable distance from the open end thereof and thus divides the container into two compartments, the smaller compartment being indicated for distinction by the numeral 6, and the end of this compartment, adjacent to 45 the open top of the container, is closed. In

the compartment 6 there is secured a longitudinally extending tubular member 7 that communicates with an opening in the closed end of the compartment 6 and with a similar opening in the bottom 5 of the container. 60 Secured in any desired manner to the tubular member 7 there are the straight arms 8 of spring members. These springs pass through suitable openings in the bottom 5 of the container and have their ends rounded 65 toward each other, as at 9. Designed to be received in the member 7 there is what I will term a cigarette receiving tube 10. The tube 10 is designed to have its outer end gripped by the spring fingers 9, and thus 70 retained in the tubular member 7 and in the container. The cigarette receiving tube 10 has its rear end closed, the said tube being of a length equalling that of the tubular member 7. Passing through the closed and 75 outer end of the receiving tube 10 there is a stem 11 having on its outer end a head 12 and on its inner end a plunger head 13.

70 The cigarette forming tube is indicated by the numeral 14, and is of a size to be snugly received in the tube 10; the same being inserted in the said tube from the top of the container 1. The tube 14 is formed with a bead or neck portion 15 and from thence with a trough extension 16. The trough 80 has angle walls, the same being directed outwardly from the center of the tube, and these walls are spaced so that the edges thereof will contact with the inner sides of the container 1.

90 A cigarette paper is arranged around the forming tube 14, and the edges thereof are pasted. The outer end of the cigarette paper is twisted to close the same. When the container is in upright position, the forming tube, with the cigarette paper therearound, is moved into the receiving tube, the plunger thereof being moved to the position illustrated in Figure 3 of the drawings. The container is then turned to the position illustrated in Figure 3 so that the tobacco from the container will fall into the trough 16. In order to break any lumps that may occur in the tobacco, I arrange in the closure 2 an agitator. The agitator defines an inner 100 blade portion 17 and an outer arched handle 18 which passes through a suitable opening in the top of the closure 2. The agitator is under the influence of a spring 19. The lower edge of the blade of the agitator is 105 110

concaved and is received in the trough 16. A pressure upon the handle 18 of the agitator will swing the same so as to break up any lumps in the tobacco received in the trough and likewise will direct the tobacco into the forming tube 14.

In order to pack the tobacco in the forming tube 14, I provide a packing rod 20. This rod passes through a suitable opening 10 in the closure 2 and is received through a slot in the handle 18 of the agitator. The rod 20 has its outer end headed, as at 21. It should have been stated that the inward movement of the forming tube 14 in the receiving tube 10 is limited by the bead or shoulder 15 on the tube 14. As previously stated, the paper is wound around the forming tube 14, and has its outer end twisted to close the same, as disclosed by Figure 7 of the drawings. The forming tube 14, with the paper thereon, is arranged in the receiving tube 10. The can or container 1 is arranged horizontally, substantially in the position illustrated in Figure 3 of the drawings, so that tobacco from the container will flow into the trough 16. The plunger rod 20 has been drawn outwardly through the closure 2 and the agitator may be operated to break up any lumps in the tobacco. The plunger tube is then reciprocated to force the tobacco from the trough into the receiving tube 10. When the tube 10 has been fully filled with the tobacco, a pressure may be exerted upon the headed end 21 of the packer rod 20 to assist in forcing the closed end of the rolled paper and the tobacco therein off of the forming tube 14, against the head 13 of the plunger. The outer head 12 of the plunger is then grasped so that the inner head 13 will contact with the closed end of the receiving tube 10, and the said receiving tube, together with the packed cigarette is drawn outwardly through the opening in the bottom 5 of the can or container 1. The packer rod 20 may be further employed for forcing the cigarette paper off of the tube 14 during this operation. When the tube 10 has been wholly removed the stem 11 may 50 be moved to bring its head 13 into contact

with the cigarette which is now in the tube 10, to assist in ejecting the said cigarette from the said tube. After a cigarette has been made and removed the tube 10 is replaced and a second cigarette paper is wound around the tube 14, is moistened to adhesively connect the lapping edges thereof and has its end twisted and closed, as above described, it being understood, of course, that the tube 14 is withdrawn from the can or container during this operation, but is thereafter reinserted in the container and received in the tube 10, so that another cigarette can be made in a manner as just described.

Having described the invention, I claim:—

A tobacco container having a hinged closure and means for latching the same on the container, a compartment in the container arranged adjacent one of the edges thereof and extending from the bottom to a point adjacent the open mouth of the container, a cylindrical member arranged in the compartment and communicating with the end of the compartment and with the bottom of the container, a tube having a plunger movable in the closed end thereof designed to be received in the cylindrical member, a cigarette forming tube adapted to have a cigarette paper arranged therearound and the edges thereof adhesively connected and designed to be received in the last mentioned tube, a rib on the forming tube limiting the movement thereof in the first mentioned tube, an angle trough on the outer end of the forming tube to direct tobacco into the said tube when the container is canted, a spring influenced agitator in the closure having a handle portion extending through said closure for agitating the tobacco in the trough, and a packing rod movable through the closure, guided through the handle of the agitator for packing tobacco in the forming chamber and for assisting in ejecting a cigarette therefrom as the plunger carrying tube is gradually moved out of the compartment.

In testimony whereof I affix my signature.

JOSE MARINO AGONCILLO.
